E. Griggs AH,

UNITED STATES PATENT OFFICE.

JACOB S. JAMMER, OF NEW YORK, N. Y., ASSIGNOR TO WESTERN ELECTRIC COMPANY,
INCORPORATED, OF NEW YORK, N. Y., A CORPORATION OF NEW YORK.

CARRIER-WAVE TRANSMISSION.

Application filed July 25, 1923. Serial No. 653,629.

This invention relates to carrier wave transmission.

Among the objects of the invention are:

5 To provide in a multiplex carrier signaling system an increase in the number of signaling channels within the given frequency range.

10 To provide a multiplex carrier signaling system wherein both telephone and telegraph signals may be transmitted simultaneously on the same carrier.

15 To provide in a multiplex carrier signaling system efficient intercommunicating means between the terminal and repeater stations.

20 To provide improved intercommunicating means between the terminal and repeater stations of a transmission system which will in no wise be affected by or affect the operation of the repeaters.

25 To provide for a plurality of multiplex carrier signaling systems efficient and economical attenuation indicating mechanism common thereto.

30 To provide efficient attenuation testing mechanism whereby each of a plurality of carrier signaling systems may be automatically and successively tested.

35 In accordance with one feature of the invention, a multiplex carrier wave telephone system has associated with one or more channels thereof telegraph transmitters for changing the magnitude of the carrier current in the channels whereby telegraph receivers will respond thereto without affecting the operation of the carrier telephone apparatus so that telephone and telegraph signals may be transmitted simultaneously on the same carrier.

40 According to another feature of the invention the terminal and repeater stations of a carrier wave signaling system are provided with sending and receiving apparatus for affording intercommunication between

45 any two or all of said stations. Such intercommunicating apparatus operates with carrier current of a frequency differing from that employed in the usual signaling channels and entirely independent of the repeaters and the carrier wave transmission apparatus of the usual channels of the system.

50 According to a further feature of the invention there is provided, at a station where

a plurality of carrier wave transmission systems terminate, an attenuation indicator 55 which may be associated with any one of such systems to measure and indicate the attenuation thereof. This attenuation indicator is responsive to a pilot frequency which is different from the usual channel 60 frequencies.

If the measured attenuation differs from the adopted standard by more than a predetermined amount, due to line changes, a signal is operated to so indicate to the station attendant, who may then communicate with the distant terminal and repeater attendants to make the appropriate adjustments to bring the transmission back to the adopted standard. Apparatus is provided 65 whereby the attenuation indicator is automatically and successively associated with the various carrier wave transmission systems to measure the attenuation thereof.

The invention will be described as applied 75 to a multiplex carrier signaling transmission system, although it will be understood that it is not limited to such a system for some of the features thereof may find application in other forms of signaling systems 80 and in other fields.

In the drawings:

Figs. 1 and 2, when placed end to end with Fig. 1 at the left, show diagrammatically a multiplex carrier telephone and telegraph system provided with the intercommunicating channel and the attenuation indicator of the invention, the indicator serving also for several other such systems, which are merely indicated.

85 Fig. 3 shows curves representing the magnitude and form of the carrier and voice side band waves in the carrier telephone and telegraph system.

90 Fig. 4 shows the operating characteristics of the rectifiers of the carrier telephone and telegraph system.

The multiplex carrier telephone and telegraph system of Figs. 1 and 2 comprises in general a main high frequency transmission 100 line ML extending between terminal stations W and E and having intermediate the terminal stations a plurality of repeater stations R.

105 The telephone channels employ different carrier frequencies, those used for transmis-

sion in one direction being grouped in a different frequency range from those employed for transmission in the opposite direction. The telegraph channels are superposed upon 5 the telephone channels in a manner to be described and employ the same carrier frequencies respectively.

An intercommunicating channel IC for communication between the repeater and 10 terminal stations is associated with the multiplex carrier telephone and telegraph system. This intercommunicating system employs but one carrier frequency, which is 15 different from that of any of the telephone and telegraph channel frequencies. Preferably, the intercommunicating channel frequency is higher than that of any of the telephone and telegraph channel frequencies.

The multiplex carrier telephone and 20 telegraph system is also provided with a pilot channel PC for measuring and indicating the gain of the transmission line and the apparatus associated therewith. The pilot frequency is different from the frequencies 25 of the telephone and telegraph channels and the intercommunicating channel.

The apparatus at the two terminal stations 30 is similar so that a description of the apparatus of one terminal will suffice.

30 Terminal station multiplex carrier telephone and telegraph system.

The multiplex carrier telephone and telegraph system has three or more telephone 35 channels upon each of which is superposed a telegraph channel arranged for two way operation. Since the channels are alike except for the constants of some of the apparatus thereof, due to the different frequencies employed, it will be unnecessary to describe more than one such channel.

There is provided at the terminal station W, for example, three telephone channels, 1, 2 and 3, an intercommunicating channel 45 IC, and a pilot channel PC, all of which are connected to the main line ML.

Telephone channel No. 1 includes a transmitting channel TC₁ and a receiving channel RC₁, which are conjugately related to a 50 low frequency telephone line L₁ by means of a transformer 5 and a balancing net work N. The telephone line L₁ usually extends to and terminates at a telephone switchboard (not shown).

55 The transmitting channel TC₁ includes a modulator M₁ and a transmitting band filter TBF₁.

The modulator M₁ may be of any well-known type, such, for example, as the electronic valve modulator of the three-electrode type disclosed in Fig. 42 of the article "Carrier current telephony and telegraphy" by Colpitts and Blackwell appearing in "Transactions of the American Institute of 60 Electrical Engineers", volume 40; 1921. Car-

rier current of the frequency assigned to this channel is supplied to the modulator M₁ from a high frequency source O₁.

The transmitting band filter TBF₁ is of the type disclosed in U. S. patents to Campbell, Nos. 1,227,113 and 1,227,114 of May 22, 1917. This band filter is designed to pass currents of the carrier frequency assigned to this channel and currents of frequencies within either the upper or lower side band thereof and to suppress currents of all other frequencies.

In order that the telegraph channel may be superimposed upon this telephone channel there is associated therewith a telegraph transmitting key 6 which, during the operation thereof, is adapted to intermittently shunt an impedance element 7, which may take the form of a non-inductive resistance, across the leads from the source of high frequency current O₁. Thus, during the intermittent operation of this transmitting key 6 the amplitude of the carrier current supplied to the modulator M₁ is alternately reduced from and restored to its normal value. Consequently the telephone signal modulated carrier current output from the modulator M₁ is intermittently changed in amplitude during the transmission of telegraph signals.

The relative amplitudes of the carrier frequency when the transmitting key 6 is open and closed is shown in Fig. 3. This figure also shows the amplitude of the voice or telephone side band currents.

The receiving channel RC₁ includes a receiving band filter RBF₁, a demodulator DM₁, an amplifier A₁, a low pass filter LPF, a high pass filter HPF, a rectifier R₁, and a telegraph receiving relay 8 which controls the usual telegraph sounder 9.

The receiving band filter is of the type disclosed in the Campbell patents, supra. It is designed to pass currents of the carrier frequency assigned to this channel and of the frequencies within either the upper or lower side band thereof and to suppress currents of all other frequencies.

The demodulator DM₁ and the amplifier A₁ may be of any well known type, such, for example, as those disclosed in Fig. 42 of the Colpitts and Blackwell article, supra.

The low pass filter LPF is of the type disclosed in said Campbell patents. It is designed to pass currents within the voice range between about 200 and 2,000 cycles frequency, and to suppress currents of higher frequencies as well as the telegraph signals below 200 cycles. The high pass filter HPF is designed to pass currents of the carrier frequency assigned to this channel and of frequencies within the telegraph side bands. Thus, these two filters separate the received telephone and telegraph signals.

The low pass and high pass filters may 130

be replaced by band filters of the type disclosed in said Campbell patents. The band filter employed in place of the low pass filter should be designed to pass currents of frequencies within the voice or speech range and to suppress currents of all other frequencies. The band filter employed in place of the high pass filter should be designed to pass currents of the carrier frequency assigned to this channel and currents of the frequencies within both or one of the telegraph side bands and to suppress currents of all other frequencies.

The rectifier R_1 may be of any well known type, such, for example, as that disclosed in Fig. 42 of the Colpitts and Blackwell article, *supra*.

The operation of the system in so far as transmission and reception of telephone signals are concerned, is well known. Therefore no description thereof will be given.

Fig. 3 shows a set of curves representing the magnitudes of the transmitted waves of different frequencies. Curve A shows the magnitude of the carrier waves when the telegraph key 6 is open, curve B the magnitude of the carrier waves when the telegraph key is closed, and curve C the magnitude of the voice side band waves.

Fig. 4 shows the characteristic curve of the rectifier R_1 . The curve D is plotted with input voltages E_0 as abscissæ against rectified currents I_D as ordinates. When the telegraph key is open, the input voltage a impressed upon the rectifier causes rectified current of magnitude x to flow; and when the telegraph key is closed, the input voltage b impressed upon the rectifier causes rectified current of magnitude Y to flow.

The operation of the telegraph channel superimposed upon the telephone channel and employing the same carrier frequency may be explained by reference to Fig. 4. When the telegraph key 6 is open, the normal amount of carrier current is flowing to line and the amount of rectifier current through the telegraph receiving relay 8 at the distant station is sufficient to hold its contact closed, thereby maintaining the circuit of the sounder 9 closed. When the telegraph key 6 is closed the amount of carrier fed to line is reduced as indicated in Fig. 3 and the amount of rectified current through the receiving relay 8 at the distant station is reduced to such an extent that the relay can no longer hold up its armature. The circuit of the sounder 9 is therefore opened. When the telegraph key 6 is again opened, the amount of rectified current through the receiving relay 8 at the distant station increases and it thereupon closes its contact, causing the energization of the sounder 9.

The amplitude of the side band frequencies (as indicated in Fig. 3) is low compared to the difference between the amplitudes of

the carrier frequencies when the telegraph key is open and closed. Consequently there is no interference between the simultaneously transmitted telephone and telegraph signals.

Intercommunicating channels.

The intercommunicating channel IC is connected to the main line ML through selective circuit ICF, which may be either an ordinary tuned circuit comprising capacity and inductance or a band filter of the type disclosed in the Campbell patents, *supra*. If the selective circuit is a band filter it should be designed to pass currents of the frequency assigned to this channel and currents of the frequencies within one or both side bands thereof and to suppress currents of all other frequencies.

The intercommunicating channel IC has associated therewith at each terminal station a transmitting channel TIC and a receiving channel RIC.

The transmitting channel TIC includes a high frequency source, such as an oscillator IO, supplying current of the carrier frequency assigned to this channel. The output circuit of the oscillator includes a work circuit connected to a transformer 10, whose secondary terminates in normally open contacts. The connection of the oscillator IO to the main line is controlled by a relay 11 having in its operating circuit a normally open transmitting key 12.

The receiving channel RIC includes an input transformer 13, a rectifier IR, and a receiving relay 14 which controls the operation of a sounder 15.

At each of the repeater stations there is provided for the intercommunicating channel transmitting and receiving apparatus to be described presently.

Pilot channel.

The pilot channel PC includes a source of high frequency currents PO connected to the main line through a selecting circuit PCF, which may be either a simple tuned circuit or a band filter of the Campbell type designed to pass currents of the pilot frequency and to suppress currents of all other frequencies.

The pilot channel PC will be described further in connection with the attenuation indicator, to be referred to more in detail hereinafter.

Repeater station.

Each repeater station R is provided with a repeater having two asymmetric repeating channels RW and RE for repeating currents in opposite directions, and the transmitting and receiving apparatus for the intercommunicating channel.

Repeater.

The repeater per se, which forms no part

of the present invention may be of the type disclosed in U. S. patent to Raibourn, No. 1,413,357, April 18, 1922, or of the type disclosed in my copending application, Serial 5 No. 640,643, filed May 22, 1923.

Each of the repeating channels includes an input filter, an amplifier, and an output filter, for further details of which reference should be made to either the Raibourn patent 10 or my copending application aforesaid.

Intercommunicating channel apparatus.

The transmitting and receiving apparatus for the intercommunicating channel is connected in shunt with the receiving channels through selective circuits WICF and EICF so as not to be affected by or affect the operation of the repeater. Apparatus is provided for receiving signals from either direction over the line. Thus, signals transmitted over the intercommunicating channel from the west line section are received by a rectifier WR, having a relay 16 in its output circuit, and the signals incoming 20 from the east line section are received by a rectifier ER which has in its output circuit a relay 17. The rectifier WR is connected to the main line ML through input transformer 18, normally closed contacts of relay 25 and selecting circuit WICF. The selecting circuits WICF 30 and EICF are similar to the selecting circuit ICF described in connection with the terminal apparatus and perform the same functions.

Operation of the receiving relay 16 causes 40 the operation of relays 21 and 22. The operation of the relay 21 causes the operation of the telegraph sounder 23. The operation of relay 22 disconnects the rectifier ER from the east line section, and connects to this line 45 section a source of high frequency current IO of the carrier frequency assigned to the intercommunicating channel. When the receiving relay 17 operates it causes the operation of relays 25 and 19. Relay 25 controls the operation of the sounder 23. The operation of relay 19 disconnects rectifier WR from the line, and connects to the line 50 the high frequency source 10. The load on the oscillator 10 is always constant due to 55 the provision of resistances 24 and 26 connected through closed contacts of relays 22 and 19 respectively to the oscillator. When either relay operates, its associated resistance is disconnected from the oscillator and 60 one of the line sections substituted therefor.

The apparatus for the intercommunicating channel at each repeater station includes also a telegraph key 27 and a relay 28, whose actuation causes the energization of relays 19 65 and 22 whereby the source of high frequency

current IO is connected to both sections of the transmission line outgoing from the repeater station.

The attendant at terminal station W desiring to communicate with any or all of the 70 repeater attendants or the attendant at the distant terminal station may do so by actuating transmitting key 12 to transmit a carrier wave modulated in accordance with a telegraph signal. Upon the closure of the 75 key, relay 11 operates, connecting the source of high frequency currents IO to the main line through the selecting circuit ICF. The currents so impressed upon the line are selected at the first repeater station by the selecting circuit WICF, and pass through the primary winding of transformer 18. The resulting induced currents in the secondary of this transformer are impressed upon the rectifier WR and the rectified current in the 80 output circuit thereof causes the operation of relay 16. Relay 16, in operating, causes the energization of relay 21 which operates the sounder 23. Relay 22 also operates disconnecting rectifier ER from the line section 85 and connecting thereto the source of high frequency currents IO. Current so impressed upon the line section from the source IO is selected by the selecting circuit 90 WICF at the next repeater station where the apparatus functions in the manner previously described. Thus, the telegraph signals are relayed from station to station and cause the operation of the sounder at each of the repeater stations and the sounder at 95 the distant terminal station E corresponding to the sounder 15 at station W. Any one of the repeater attendants may likewise communicate with the other repeater attendants and terminal attendants by actuating key 27 100 to transmit the intercommunicating channel frequency modulated in accordance with telegraph signals.

Attenuation indicator mechanism.

As already explained, the multiplex carrier telephone and telegraph system of Figs. 1 and 2, represented as a whole by reference characters SI, is provided with a pilot channel over which a pilot frequency is either 110 continuously or periodically transmitted for controlling the attenuation indicator mechanism.

Fig. 2 indicates two additional multiplex carrier signaling systems S_2 and S_3 terminating at the terminal station E. These two systems, S_2 and S_3 , may be of the same type as system S_1 shown in detail in Figs. 1 and 2 and previously described. These two indicated systems are provided with 120 pilot channels like that shown and described in connection with the system S_1 . Attenuation indicator mechanism AIM located at the terminal station E may be associated 125 with the transmission line of any one of the 130

multiplex signaling systems terminating at station E for the purpose of measuring and indicating the net attenuation thereof.

Each of the systems is provided with a 5 selective circuit such as a pilot channel filter PCF so as to select the pilot frequency transmitted over the line from the distant terminal station.

The transmission lines of the various multiplex signaling systems terminating at the station E may be and usually are of different lengths. An adjustable resistance network RN is therefore associated with each 10 of the systems so that upon adjustment thereof, the equivalent length may be made the same for all of the transmission lines.

The attenuation indicator mechanism includes means for automatically and successively connecting itself to the transmission lines of the multiplex signaling systems terminating at station E. The indicator mechanism when connected to one of the transmission lines responds to variations in strength of the received pilot frequency 15 and controls an indicator, the actuation of which indicates the general condition of the net attenuation of the line. For this purpose the indicating mechanism employs a kind of potentiometer circuit, the condition 20 of balance or unbalance of which determines the direction and extent of adjustment necessary to bring the net attenuation of the transmission line back to the adopted standard.

35 The potentiometer circuit includes a galvanometer 30 for indicating the balanced or unbalanced condition of the circuit. The relation between this galvanometer and the indicator controllers is secured through the 40 medium of an automatic controlling apparatus generally indicated at 31.

This controlling apparatus of itself forms no part of the present invention and has not been illustrated in detail since it may comprise 45 any suitable or well-known arrangement by which a power shaft such as 32 is held stationary when the galvanometer 30 is in its zero or mid-position and is automatically rotated in one direction or the 50 other dependent upon the direction of deflection of the galvanometer. Such rotation persists continuously or by steps until the galvanometer is again brought to its zero position. One specific system for accomplishing this is shown in U. S. patent to 55 Brewer, No. 1,356,804 of October 26, 1920, and for a more complete description of the circuits and mechanism involved this patent may be referred to. The controlling apparatus 60 31 includes a motor 33 which when its circuit is closed is driven continuously from a source of power 34.

The galvanometer 30 in series with a portion of potentiometer 34 is connected across 65 bridge points of a Wheatstone bridge cir-

cuit 35 which has connected thereto a battery 36 through an adjustable resistance 37. The potentiometer 34 is connected to the output circuit of a rectifier 38. The plate-cathode path of rectifier 38 forms one arm 70 of a Wheatstone bridge circuit whose other arms are formed by resistances 39, 40 and 41. The rectifier plate circuit battery 42 is connected across this Wheatstone bridge circuit. The rectifier input circuit is coupled 75 by means of transformer 43 to the output circuit of an amplifier 44 whose input circuit is connected to the terminals of a potentiometer 45. One terminal and an adjustable contact 46 of the potentiometer 45 80 are connected to conductors 47 and 48 multiplied to normally open contacts of relays 49, 50 and 51 by which the attenuation indicator mechanism is connected to the respective transmission lines. 85

When the attenuation indicator mechanism AIM is connected to one of the transmission lines, and the attenuation of such line is normal, the grid potential of amplifier 44 will be normal. Consequently the 90 cathode-anode impedance of rectifier 38 will be such as to set up a certain potential difference across potentiometer 34. The movable contact may then be adjusted until the potential difference due to the rectifier across 95 points a and b of the Wheatstone bridge circuit 35 equals the potential difference across the same points due to battery 36. The battery 36 is so poled that these potential differences are opposite, whereby the 100 galvanometer 30 will remain in its zero or mid-position. This particular type of rectifier circuit forms no part of the present invention, but is disclosed and claimed in Patent No. 1,579,708, dated April 6, 1926. 105 The potentiometer winding 45 is carried by a disc 52 fastened to and rotatable with the shaft 32. The shaft 32 also carries two cams 53 and 54 which respectively control indicator lamps 55 and 56, the circuits of which 110 include a relay 57 for opening the motor circuit and closing the circuit of an audible signal 58. The motor 33 is provided with a shaft 59 which is rotated continuously 115 while the motor is operating. This shaft carries a plurality of cams C₁, C₂, C₃ and C₄ which are staggered angularly so that only one of such cams is operative at a time to close contacts controlled thereby. There 120 is one of these cams for each of the multiplex signaling systems S₁, S₂ and S₃. Cam C₁ controls relay 49 and its associated signal lamp 60. Cam C₂ controls the relay 50 and its associated signal lamp 61. Cam C₃ controls relay 51 and its associated signal lamp 62. Cam C₄ may control a similar relay and signal lamp associated with another signaling system, not shown. 125

Assume that the motor 33 is operating and that cam C₁ has just closed its contact 130

Relay 49 thereupon operates to connect the transmission line ML of system S_1 to the conductors 47 and 48 extending to the potentiometer 45 and amplifier 44. At the 5 time relay 49 operates, signal lamp 60 is lighted to indicate to the attendant that the attenuation indicator mechanism is connected to system S_1 .

If, due to a change in line attenuation or 10 to other causes, the net attenuation of the system is below normal, the amount of energy from the transmission line ML delivered to the amplifier 44 will be less than normal. Consequently the cathode-anode 15 impedance of rectifier 38 will be greater than normal. The galvanometer will be deflected from its zero position. The shaft 32 thereupon is rotated in a clockwise direction. Such rotation of the shaft 32 causes the rotation 20 of the disc 52 carrying the potentiometer 45 and the contact 46 is shifted along the potentiometer so as to increase the input energy of the amplifier 44. If the energy incoming from the line is but slightly below 25 normal there will be but a slight adjustment of potentiometer 45 and the attenuation indicator mechanism will be disconnected from the system S_1 without further portions of the indicator mechanism coming into play. 30 However, if the amount of energy incoming from the transmission line is considerably less than normal, there will be such an adjustment of potentiometer 45 that the cam 54 will close its contact, thereby lighting the 35 indicating lamp 56 and causing the energization of relay 57. Relay 57 upon operating, opens the motor operating circuit and causes the operation of the audible signal 58. The operation of the audible signal 58 40 is an audible indication to the attendant that the apparatus of the transmission line ML of the connected system needs adjustment. The lighting of the lamp 56 indicates to the attendant that the adjustment must be in a 45 direction to increase the gain of the repeater to compensate for the increased attenuation of the line. The lighting of lamp 60 indicates to the attendant that the necessary adjustment must be made along the transmission 50 line of system S_1 . The particular setting of the potentiometer 45 at the time the motor 33 stops, indicates to the attendant roughly the amount of adjustment necessary to bring the attenuation of the system back 55 to the adopted standard.

The attendant at the terminal station E may thereupon communicate with the repeater attendants by means of the intercommunicating channel previously described, 60 and instruct such repeater attendants to make the necessary adjustments.

After the adjustments have been made and the system S_1 thereby restored to normal transmission efficiency the attendant at 65 terminal station E may again start the mo-

tor of the indicating mechanism by closure of key 63. This key 63 will be maintained closed until such time as the cam 54 disengages its contact so as to allow the release of relay 57. While the shaft 32 is being rotated to cause cam 54 to open its contact, the potentiometer 45 is being varied toward its position corresponding to normal line attenuation.

If the amount of energy incoming from 75 the line is above normal, there will be such a deflection of the galvanometer 30 as will cause the counter-clockwise movement of shaft 32. If the amount of energy incoming from the line is sufficient, the shaft 32 80 will continue its counter-clockwise movement until cam 53 closes its contact. The lamp 55 thereupon lights and relay 57 operates to stop the motor and operate the audible signal 58.

If when system S_1 is connected to the indicator mechanism, the incoming energy is not sufficient to cause either of the cams 90 53 or 54 to close its contact, the motor will not be stopped but will continue to rotate 95 shaft 59. The continuous rotation of the shaft 59 will cause cam C_1 to open its contact, thereby disconnecting the system S_1 from the indicator mechanism. Cam C_2 will thereafter close its contact and through 100 the operation of relay 50 connect system S_2 to the indicator mechanism which will test the transmission line of this system. If no 105 adjustments of the repeater apparatus as indicated by the lighting of lamp 55 or lamp 56 are necessary, the motor will continue to operate and cam C_2 will open its contact. System S_2 is thereby disconnected from the indicator mechanism and subsequently cam C_3 closes its contact to cause the operation of 110 relay 51 which connects system S_3 to the indicator mechanism.

The relays 49, 50 and 51 are provided with 115 normally closed contacts which are connected in series. The circuit including these normally closed contacts is connected in shunt of the galvanometer 30, so that when none of the transmission lines is connected to the indicator mechanism the galvanometer 30 is short-circuited. Consequently, there is no deflection of the galvanometer 30 due to the unbalance of the Wheatstone bridge circuit 35 when no transmission line is connected to the indicator mechanism.

The invention set forth herein is, of course, susceptible of various other modifications and adaptations.

The invention claimed is:

1. A plurality of transmission lines converging and terminating at a station, testing apparatus thereat for indicating the attenuation on a connected line, and means for automatically and successively connecting the testing apparatus to the lines.

2. A plurality of signaling systems having transmission lines which converge and terminate at a station, testing apparatus at the station, means for connecting the testing apparatus to any one of the lines, means included in the testing apparatus responsive to currents incoming from the connected line, signaling devices associated with the testing apparatus and controlled by said responsive means to indicate the condition of the line and means controlled by currents incoming from the connected line for controlling the means for connecting the testing apparatus to the lines. 10
3. In combination, a plurality of high frequency carrier current transmission lines radiating from a station, a pilot frequency channel associated with each transmission line, attenuation measuring and indicating mechanism common to the lines and located at the station, and means for successively connecting said mechanism to the lines, said mechanism including means responsive to frequencies transmitted over the pilot channel of the connected line and having signaling devices controlled by said frequency responsive means to indicate whether the attenuation of the connected line is above or below a predetermined value. 20
4. A plurality of transmission lines converging and terminating at a station, testing apparatus thereat, switching means for successively connecting said testing apparatus to said lines, signaling devices controlled by said switching means to indicate the particular line to which said testing apparatus is connected, and means for controlling said switching means by currents incoming from the connected line. 30
5. A plurality of transmission lines of variable attenuation converging and terminating at a station, an attenuation indicator thereat, means for successively connecting said attenuation indicator to said lines, and means including said indicator to selectively indicate an increase or decrease in the attenuation of the connected line. 40
6. A plurality of transmission lines of variable attenuation converging and terminating at a station, an attenuation indicator thereat, and means for successively connecting said attenuation indicator to said lines, said indicator including a signaling device to indicate abnormal attenuation conditions on the connected line, and a signaling de- 50
- vice to indicate the particular character of such abnormal conditions. 60
7. In a system of transmission regulation, a plurality of transmission lines of variable attenuation over which pilot waves are transmitted, an indicator common to said lines, means including a plurality of relays for successively connecting said indicator to said lines, means including said indicator responsive to the pilot wave transmitted over the connected line to indicate the condition of said line, and means controlled by said relays for disabling said indicator when said indicator is not connected to any of said lines. 70
8. In a system of transmission regulation, a plurality of transmission lines of variable attenuation over which pilot waves are transmitted, testing apparatus, switching means for connecting said testing apparatus to any one of said lines, signaling devices controlled by said switching means to indicate the particular line to which said testing apparatus is connected, means including the testing apparatus responsive to the pilot wave incoming over the connected line, and signaling devices associated with said testing apparatus and controlled by said responsive means to indicate the condition of the line. 80
9. A plurality of transmission lines converging and terminating at a station, testing apparatus at the station for indicating the attenuation on a connected line, means for automatically and successively connecting said apparatus to the lines, and means controlled by currents incoming from the connected line for controlling the means for connecting the testing apparatus to the lines. 90
10. A plurality of transmission lines converging and terminating at a station, testing apparatus at the station for indicating the attenuation on a connected line, means for automatically connecting the testing apparatus to the lines, signalling devices, and means controlled by currents incoming from the connected line for controlling the means for connecting the testing apparatus to the lines and for controlling said signaling de- 100
- 105

In witness whereof, I hereunto subscribe my name this 17th day of July A. D., 1923.

JACOB S. JAMMER.
